G. J. SIMON

CULINARY UTENSIL

Filed March 19, 1927

Inventor

G. J. Simon

Watson E. Coburn
Attorney

UNITED STATES PATENT OFFICE.

GEORGE J. SIMON, OF ST. LOUIS, MISSOURI.

CULINARY UTENSIL.

Application filed March 19, 1927. Serial No. 176,802.

This invention relates to culinary utensils and more particularly to a device for turning eggs, flapjacks or the like.

An important object of the invention is to provide a device of this character which may be relatively cheaply constructed, which is durable and efficient in service and a general improvement in the art.

A further object of the invention is to provide a device wherein the support for the turner blades and the actuating mechanism can, for the main portion, be formed from a single length of spring wire.

These and other objects I attain by the construction shown in the accompanying drawings, wherein for the purpose of illustration is shown a preferred embodiment of my invention and wherein:

Figure 1 is a plan view of a culinary utensil constructed in accordance with my invention;

Figure 2 is a section on the line 2—2 of Figure 1;

Figure 3 is a section on the line 3—3 of Figure 1;

Figure 4 is a fragmentary side elevation of the forward end of the utensil.

Referring now more particularly to the drawings, the numeral 10 generally designates a handle formed by bending a resilient wire in U-shape. The end of one of the arms 11 of the U is slightly shorter than the other arm and is provided at its terminus with a head 12 directed transversely of the U. From the center of this head, a depending arm 13 extends, this arm having at its lower end an eye 14 receiving a bearing 15 at a groove 16 formed therein. It will be obvious from an inspection of Figure 2, that the head 12, arm 13 and eye 14 can all be formed from the same length of wire from which the handle 10 is formed, by first bending the terminal portion of the arm 11 transversely of the U to provide a transverse bar 17. The free end of the bar 17 is reverted, as at 18, in spaced relation to the bar 17 and extends to a point approximately centrally to the bar. From this point, it is bent downwardly to form a portion of the arm 13, as indicated at 19. It is then bent to form the eye 14, after which it extends upwardly in parallel relation to the bar 19 to the level of the revert 18. It is then bent at right angles to form a continuation 20 of this revert and its free end

is secured to the arm 11 at the junction of the bar 17 therewith.

It will be obvious that this construction will provide in the head a transversely extending slot 21. The longer arm 22 of the U extends outwardly over the head 12 and is then reverted in spaced relation, as indicated at 23. This revert is passed through the slot 21 formed in the head and at the inner face of the head is provided with a downwardly extending arm 24. Directed through the bearing 15 is a shaft 25, which is provided at one end of the bearing with an enlargement 26 and at the opposite or rear end of the bearing has secured thereto an arm 27 having a slot 28 formed therein. The lower end of the arm 24 has an angular extension 29 extending into the slot 28 of the arm. The forward end of the shaft has secured thereto a blade 30, such as is ordinarily applied to culinary turners. The arms of the U being formed of spring material, the arm 22 normally has its revert 23 disposed at that end of the slot remote from the arm 11 and when the arm 22 is in its normal position, the blade 30 is in a plane parallel to the handle 10 and has one face thereof arranged uppermost. By applying pressure to the arms 22 and 11, causing the same to move toward one another, it will be obvious that the connection of the arm 24 with the arm 28 of the shaft will cause this shaft to be oscillated, thereby oscillating the blade through substantially one-half of one revolution and causing an article supported thereby to be inverted. As soon as the pressure is released, the blade returns to its normal position.

It will be obvious that a device of this character may be very readily and cheaply produced and will be durable and efficient in service. It will furthermore be obvious that the construction hereinbefore set forth is capable of a certain range of change and modification without materially departing from the spirit of the invention, and I accordingly do not limit myself to such specific structure except as hereinafter claimed.

I claim:

1. A culinary utensil of the character described including a handle comprising a substantially U-shaped resilient element, one of the arms of the handle being shorter than the other and being provided with a head extending transversely of the U, said head

having a transversely extending slot, an arm depending from the head, a bearing supported from the lower end of the arm, a shaft rotatable in said bearing and having a blade upon one end thereof and upon the opposite end thereof an arm provided with a longitudinally extending slot, the other arm of the handle being extended through the slot of the head and having a depending arm the lower end of which is engaged in the slot of the arm of the shaft, the last named arm of the blade by its inherent resiliency being normally disposed at the end of the slot remote from the first named arm of the handle, said blade, when the last named arm of the handle is in normal position, being disposed in a plane substantially paralleling the handle.

2. A culinary utensil of the character described including a handle comprising a substantially U-shaped resilient element, one of the arms of the handle being shorter than the other and being provided with a head extending transversely of the U, said head having a transversely extending slot, an arm depending from the head, a bearing supported from the lower end of the arm, a shaft rotatable in said bearing and having a blade upon one end thereof and upon the opposite end thereof an arm provided with a longitudinally extending slot, the other arm of the handle being extended through the slot of the head and having a depending arm the lower end of which is engaged in the slot of the arm of the shaft, the last named arm of the blade by its inherent resiliency being normally disposed at the end of the slot remote from the first named arm of the handle, said blade, when the last named arm of the handle is in normal position, being disposed in a plane substantially paralleling the handle, said head, its arm and eye receiving the bearing being formed integrally with the end of the first named arm of the handle.

of the handle, said blade, when the last named arm of the handle is in normal position, being disposed in a plane substantially paralleling the handle, said bearing having a circumferential slot, the lower end of the arm depending from the head receiving the bearing at said slot.

3. A culinary utensil of the character described including a handle comprising a substantially U-shaped resilient element, one of the arms of the handle being shorter than the other and being provided with a head extending transversely of the U, said head having a transversely extending slot, an arm depending from the head, a bearing supported from the lower end of the arm, a shaft rotatable in said bearing and having a blade upon one end thereof and upon the opposite end thereof an arm provided with a longitudinally extending slot, the other arm of the handle being extended through the slot of the head and having a depending arm the lower end of which is engaged in the slot of the arm of the shaft, the last named arm of the blade by its inherent resiliency being normally disposed at the end of the slot remote from the first named arm of the handle, said blade, when the last named arm of the handle is in normal position, being disposed in a plane substantially paralleling the handle, said head, its arm and eye receiving the bearing being formed integrally with the end of the first named arm of the handle.

In testimony whereof I hereunto affix my signature.

GEORGE J. SIMON.
